(57) **CLAIM**

The ornamental design for a support mechanism with articulated arm for a microphone, as shown and described.

DESCRIPTION

FIG. 1 is a perspective view of a support mechanism with articulated arm for a microphone.

FIG. 2 is a left side view thereof.

FIG. 3 is a right side view thereof.

FIG. 4 is a top view thereof.

FIG. 5 is a bottom view thereof.

FIG. 6 is a rear view thereof.

FIG. 7 is a front view thereof.

FIG. 8 is a fully opened perspective view thereof, showing my new design in full lines with broken lines showing of environmental association matter being for illustrative purposes only and forming no part of the claimed design; and, FIG. 9 is a fully closed perspective view thereof, showing my new design in full lines with broken lines showing of environmental association matter being for illustrative purposes only and forming no part of the claimed design.
